CLAIM

I claim the ornamental design for a cigar glass, as shown and described.

DESCRIPTION

FIG. 1 is a top, front perspective view of a cigar glass;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is an environmental perspective view of FIG. 1. In the drawings, the broken lines depict environment and define the bounds of the claim, and form no part of the claimed design.
